UNITED STATES PATENT OFFICE.

JOHN SACHAR, OF KATO, PENNSYLVANIA.

BULLET-DEFLECTOR FOR ORDNANCE.

1,159,104.

Specification of Letters Patent.

Patented Nov. 2, 1915.

Application filed June 15, 1915. Serial No. 34,172.

To all whom it may concern:

Be it known that I, JOHN SACHAR, a subject of the Emperor of Austria-Hungary, residing at Kato, in the county of Center and State of Pennsylvania, have invented certain new and useful Improvements in Bullet-Deflectors for Ordnance, of which the following is a specification.

This invention relates to new and useful improvements in bullet deflector for ordnance.

The primary object of this invention is to provide an adjustable deflecting shield for guns and cannons readily positionable in front of the artillerymen during the loading operation although permitting a sufficient sight opening for aiming the gun for firing.

A further object of the device is the provision of a bullet-proof canopy forwardly adjustable for the prevention of injury to the artillerymen when loading and firing the cannon.

A still further object is to provide a bullet shield which is easy and cheap to manufacture and which at the same time affords the requisite strength and has serviceable adjusting means for supporting the same for use at any desired position.

With these general objects in view and others that will appear as the nature of the invention is better understood, the same consists in the novel combination and arrangement of parts hereinafter fully described, illustrated in the accompanying drawings and then claimed.

In the drawings forming a part of this application and in which like designating characters refer to corresponding parts throughout the several views:—Figure 1 is a side elevation of a cannon provided with the present device, and Fig. 2 is a rear elevation thereof.

Referring more in detail to the drawings, a cannon 10 of substantially the usual form is herein illustrated mounted upon a substantially triangular shaped carriage frame 11. The said carriage frame has the base portion 12 thereof secured to an axle 13 while ground wheels 14 are journaled upon the opposite ends of the said axle. The said carriage frame extends rearwardly from the said axle 13 and has its pointed end or apex portion 15 normally positioned upon the ground after the manner of the usual gun carriage.

A bullet shield 16 is formed of any de-

sired bullet resisting material and consists of a main shield portion 17 substantially semi-circular in cross section and provided with obliquely arranged supporting legs 18 secured at their tops to the under side of the said portion 17 and adjacent the forward end thereof. A forward shield portion 19 of the substantial form of an inverted scoop is forwardly secured to the main shield portion 17 and forms a forward continuation thereof slightly angularly positioned with respect thereto.

The supporting legs 18 of the shield are adjustably arranged through longitudinal slots 20 in the opposite sides 21 of the frame 11 and are maintained at the desired adjustment by means of pins 22 positionable through perforations 23 in the said legs 18 and frame sides 21. Arms 24 are pivoted to the legs 18 adjacent their upper ends and are vertically adjustably positioned within receiving slots 25 in the frame base 12. Adjusting pins 26 are adapted to be positioned through the desired one of several perforations 27 in the arms 24 and removably arranged through side perforations 28 in the said base 12.

From this detailed description of the invention, it will be apparent that the artillerymen may remove the legs 18 from the side slots 20 and then tilt the shield 16 upon the pivotal connections 29 between the said arms and legs and thus engage the forward end of the shield portion 19 with the top of the gun 10, an inverted V-shaped notch 30 being arranged in the forward edge of the shield for seating upon the top of the gun although allowing sufficient room between the top of the gun and the shield to allow the artillerymen to accurately sight or aim the gun and train the same upon the enemy with less liability from injury by the enemy by reason of the partial protection offered by the said shield. The shield may be also elevated and adjusted in its position as desired by means of the pins and perforations hereinbefore referred to which are provided for both the legs 18 and arms 24. A serviceable protection is thus afforded for cannons which is of simple construction and adds efficiency to the ordnance during a battle.

While the form of the invention herein shown and described is what is believed to be the preferred embodiment thereof, it is nevertheless to be understood that minor changes may be made in the form, propor-

tion and details of construction without departing from the spirit and scope of the invention as claimed.

What I claim as new is:—

- 5 1. A shield for a gun comprising in combination with the carriage thereof, of a bullet resisting angularly formed shield substantially semi-circular in cross section and having an inverted V-shaped notch at its forward end, mounting legs upon the said shield adjustably and pivotally secured to the said carriage and adjusting arms for the said shield pivotally connected between the said legs and carriage.
- 10 2. A device of the class described comprising in combination with a gun carriage having two longitudinal slots of relatively different lengths arranged at the opposite sides thereof, a shield formed of bullet-proof material and having a main portion
- 15 and a forward portion angularly secured together and being substantially semi-circular in cross section, the said front portion being substantially scoop-shaped and having an inverted V-shaped side opening in the down curved front edge thereof and positioned directly above the gun, converging legs angularly secured to the under forward portion of the said main shield portion and positionable through the said relatively longer slots, adjustable retaining means for the said legs, arms pivotally connected adjacent the upper ends of said legs and longitudinally slidably positioned through the said relatively shorter slots and adjustable retaining means for the said arms.
- 20 In testimony whereof I affix my signature.

JOHN SACHAR.
